UNITED STATES PATENT OFFICE.

CORYDON L. PRINDLE, OF EVANSTON, ILLINOIS.

PERIODICAL-FILE.

SPECIFICATION forming part of Letters Patent No. 708,169, dated September 2, 1902.

Application filed July 5, 1901. Serial No. 67,147. (No model.)

To all whom it may concern:

Be it known that I, CORYDON L. PRINDLE, a citizen of the United States, residing at Evanston, in the county of Cook and State of Illinois, 5 have invented a new and useful Improvement in Periodical-Files, of which the following is a specification, reference being had to the accompanying drawings.

My invention relates to improvements in 10 devices for filing periodicals and similar articles for temporary or permanent preservation, the object being to produce a file which shall combine the features of being completely adequate to the purpose, easily used, and of 15 sightly and pleasing appearance.

In the accompanying drawings, by which 20 my invention is illustrated, Figure 1 is a partial perspective view of the file in an open position; Fig. 2, a view of the peculiar needle used in my invention with the binding-cord 25 attached, illustrating the method of adjusting the needle immovably upon the cord. Fig. 3 is a longitudinal section of the locking device to be described, together with a view 30 of the corresponding cord attachment on the opposite side. Fig. 4 is a view of the filing-eyelet used in my invention, Fig. 5 illustrating the manner of applying to said eyelet the filing-stiletto shown in Fig. 7. Fig. 6 illustrates the method of filing different articles, 35 and Fig. 8 shows a convenient combination of the filing-stiletto with a metallic paper-cutter.

In my invention the covers of the file *a a*, 40 Fig. 1, are made in the usual manner of book-covers, with a flexible back *b*. To the inner lower edges of the covers are flexibly attached, respectively, the front and back binding-strips *c* and *d*, as shown, said strips being usually made of press-board about one-half of an inch in width and nearly the length of the covers and being covered to correspond with the finish of the file. To the front binding-strip the fixed ends of the binding-cord 45 *e e* are attached, the cord engaging the articles filed and being attached to the opposite binding-strip *d* by means of the retaining-locks *ff*, Fig. 1. (More fully shown in Fig. 3.) The binding-cord may be conveniently and 50 tastefully attached to the front binding-strip by means of a suitable flat metallic shank-button, to which the cord is fastened and

passed through the eyeleted perforations *g g*. To the binding-cord is loosely attached the peculiarly-formed needle *h*. The eye of said needle extends longitudinally from the center of the head *i* to a notched opening in the side which forms the recessed shoulder *j*. The knot which terminates the cord being drawn against the shoulder *j* prevents the unthreading of the needle. Also the knot being covered in the recess does not interfere with the insertion of the needle and cord through an eyelet or unnecessarily enlarge or mutilate a perforation made by the needle. The needle 65 has also an inwardly-diminishing diagonal slot *k* in the side, between the shoulder and the point, into which the cord is drawn to prevent its slipping or becoming loose.

In operation the needle and cord having 70 been inserted through the eyelets or perforations of the articles being filed and the cord drawn taut, the needle is slipped down the projecting length of the cord closely against the last file, and the cord, wound partly around 75 the needle, is then drawn tightly into the slot, as shown in Fig. 2.

The retaining clasp or lock *ff*, Fig. 1, in section in Fig. 3, attached to the back strip *d*, consists of the inner plate *l*, fixedly attached by the rivets *p q*, having a perforation *m* directly opposite the corresponding attachment of the cord on the front strip to permit the passage of the needle and cord, the pocket *n* for inclosing the needle, and the 80 cap *o*, which is pivotally adjustable on the rivet *q*. With the cap *o* turned to the side to uncover the pocket *n*, as shown by *o* at the bottom of Fig. 1, the needle, made fast to the cord in the manner described, is inserted 85 through the opening *m* and pressed down into the pocket, when the cap is closed over it and holds it firmly in place, the needle and cord being concealed from view, as shown by *o* at the top of Fig. 1.

Periodicals and similar articles to be filed are attached to the cord by means of a filing-eyelet, which is made preferably of wire in the form shown in Fig. 4. The eye *r* of the eyelet, formed, as shown, by a projecting 90 semicircular curvature of the wire between the extremities, is adapted to be inserted outwardly through a fold to engage the binding-cord, as shown by 1 and 2, Fig. 6. In the 95

case of pamphlets, &c., of medium thickness one eyelet at each end will be sufficient, inserted as shown by 2, Fig. 6; but magazines of the usual thickness should be supplied 5 with two eyelets at each end, inserted through the folds near the front and back, as shown by 1, Fig. 6. Obviously letters and loose sheets can be readily filed by inserting the needle and cord directly through them at a suitable 10 distance from the edge, as shown by 3, Fig. 6, and pictures and other articles that would be injured by perforation can be attached to the binding-cord by means of eyelets in common use in the manner shown by 4, Fig. 6. 15 It being inconvenient and sometimes impracticable to insert the filing-eyelets without the aid of an instrument adapted to the purpose, I have devised a filing-stiletto for such use, which is shown in Fig. 7. The filing-stiletto 20 consists of a pointed metallic blade or stem with a suitable handle, which is provided adjacently to its perforating-point *t* with a shoulder *u*, adapted to engage the eyelet in the manner shown in Fig. 5 and carry the projecting eye *v* through the perforation in the 25 fold made in advance of it by the point of the stiletto. The shoulder *u* is conformed to the eye and grooved in order to securely hold the eyelet. The filing-stiletto may be conveniently combined with a metallic paper-cutter, 30 as shown in Fig. 8.

What I claim as my invention, and desire to secure by Letters Patent, is—

1. In a binding or filing mechanism a needle 35 with the eye extending longitudinally from

the head to a notched opening in the side, said opening forming a recessed shoulder to retain the knotted end of the binding-cord, in combination with the cord *e*, stays *c* and *d* and locking device *f*, substantially as described. 40

2. In a binding or filing mechanism a needle having adjacent to the eye an inwardly-diminishing slot in the side, said slot being adapted to have the binding-cord drawn securely therein, in combination with the locking device *f*, cord *e* and stays *c* and *d*, substantially as described. 45

3. In a binding or filing mechanism the locking device *f*, consisting of a fixed inner plate *l* having an aperture *m* for the insertion 50 of the needle, a pocket *n* to inclose the needle, and a movable cap *o* to confine and conceal the needle, in combination with the stays *c* and *d*, and the needle *h* and cord *e*, said needle being adapted to the adjustment of 55 the cord immovably thereon, substantially as described.

4. In a binding or filing mechanism the combination of the eyelets *r's*, adapted to be inserted through the folds of a signature and 60 engage the binding-cord, the cord *e* and stays *c* and *d*, with the needle *h* and lock *f*, said needle and lock coöperating to secure to the stay *d* the free end of the binding-cord, substantially as described.

CORYDON L. PRINDLE.
